UNITED STATES PATENT OFFICE.

LEWIS V. MATHER, OF DETROIT, MICHIGAN.

ELECTROPLATING APPARATUS.

Application filed February 6, 1922. Serial No. 534,289.

To all whom it may concern:

Be it known that I, LEWIS V. MATHER, a citizen of the United States of America, residing at Detroit, in the county of Wayne 5 and State of Michigan, have invented certain new and useful Improvements in Electroplating Apparatus, of which the following is a specification, reference being had therein to the accompanying drawings.

10 The invention relates to apparatus for the electro-plating of articles and it is the object of the invention to obtain a construction with which the articles to be plated are progressively advanced through the 15 electrolytic bath and are maintained in constant electrical connection with the cathode during advancement. It is a further object to avoid deposition of metal on the cathode bus bar. Also, to continuously 20 change the point of contact with the work without interruption of the current, thereby avoiding the shielding of any part of the surface from the metallic deposit. A further object is to provide contact members 25 for conveying the current into the work, together with means for preventing the building up of deposits on said members. With these and other objects in view the invention consists in the construction as 30 hereinafter set forth.

In the drawings:

Figures 1 and 1^a show opposite end portions of the machine in side elevation;

Figures 2 and 2^a are plan views corresponding to Figures 1 and 1^a;

Figure 3 is a cross-section;

Figure 4 is an enlarged cross-section showing the cathode bus bars and means for protecting the same and for drawing off the 40 current;

Figure 5 is a horizontal section through the part shown in Figure 4;

Figure 6 is a side elevation thereof; and

Figure 7 is an enlarged section similar 45 to a portion of Figure 3 showing certain details of construction.

While my apparatus is suitable for electro-plating of various articles, I have shown and specifically described an arrangement 50 designed for the plating of vehicle wheel rims. A is the tank which contains the electrolyte and which is preferably formed of reinforced concrete. Within this tank is arranged a framework of insulating material 55 preferably of wood, and including vertical posts or uprights C arranged in

rows longitudinally and transversely of the tank. These uprights are connected by transverse bracing bars C near the bottom of the tank and by transverse bars D at 60 the top thereof, the uprights extending above the top to form a super-framework. Upon the transverse bars C are arranged longitudinally extending runways E, which are inclined slightly upward from the entrance end of the tank to the delivery end. A plurality of runways are arranged in parallelism suitably spaced from each other. Each runway is provided with side flanges F which prevent the rims from running off 70 the track and above the runways and secured to the posts B are the guides G for the work conveyor.

To conduct the current into the work cathode, bus bars are required, but there 75 is great difficulty encountered in the arrangement and protection of such bus bars. Thus if the bars are placed below the surface of the electrolyte and are exposed to the solution, they will be subject to continuous deposition of metal. On the other hand, if the bus bars are above the solution, some means must be provided for conducting the current downward therefrom and into the work. One of the features of my 80 improvement is an arrangement of bus bars immediately adjacent to the path of the work but so protected as to avoid deposition of metal thereon. These bars cooperate with a work conveyor formed chiefly of insulating material but containing conductor 85 elements which are in electrical contact both with the bus bars and with the work. Thus the current derived from the bus bars is conducted into each rim or other articles 90 which is propelled by the conveyor along 95 the runway B, so that there is continuous deposition of metal upon the work while travelling through the tank.

In detail, the guides G are channel-shaped 100 and extend longitudinally of the tank, being preferably formed of wood. Within these channels are the bus bars H and in front of the bus bars and closing the channel are travelling links I of a conveyor chain, also 105 preferably formed of wood. The width of the link is such as to practically fill the channel with only sufficient clearance to permit of free movement, and the ends of the links are mortised to overlap adjacent links 110 to which they are pivotally attached. The pivotal attachment is formed by shafts J

which extend between the highways G in the path of the work and at the center of each shaft is a roller K for contact with the work. The portions of the shaft between the roller 5 and the links is provided with a protecting insulating cover, preferably formed of rubber tubes L sleeved thereon. The shafts are also shouldered at the point of engagement with the links as indicated at J' and the 10 portions J² of reduced diameter which pass through the links form the pivotal connection therefor. At the inner end of the portion J² is a pintle J³ which engages slots M in spring contact members M' which bear 15 upon the bus bar. These contact members M' are preferably attached at their outer ends to the links by bolts N and intermediate said point of attachment and the portion engaging the shaft J said contacts are 20 bowed outward to be pressed into yielding contact against the bus bar H. Thus while the bus bar is shielded from the body of the electrolyte outside of the channel members G by the links I, the current is nevertheless 25 conveyed from said bus bars into the shafts J and rollers K and from the latter into the body of the work. The links I together form an endless chain which passes around sprockets O at opposite ends of the tank and 30 returns through a path above the surface of the electrolyte. In this return path are arranged troughs P which receive the rolls K and which contain a stripping solution that will dissolve off the electrolytic deposit 35 upon said rolls, the rolls themselves being formed of an alloy which is unaffected by the stripping solution. Thus during the interval in which the rolls K are returning, they will be completely stripped of any 40 electrolytic deposit so that building up of the rolls is avoided.

The anodes are preferably arranged in the space between adjacent rows of work and are preferably of the following construction: A are anode bus bars arranged above the surface of the electrolyte and extending longitudinally of the tank, being supported from the insulator framework therein. R are the anode stoppers which are suspended 45 from the bus bars and extend downward into the electrolyte in the space between posts C and adjacent to the guides G. Usually the point of attack in the anode is a short distance below the top of the electrolyte and frequently the plate will be completely eaten throughout this point, while a considerable mass in the lower portion is still intact. I have discovered that by embedding in the anode plate a bar of higher 50 electrical conductivity than the metal of which the anode is composed, a more uniform action upon the surface is obtained. As shown, a copper conductor loop R' is 55 cast in the center of the anode plate formed 60 of zinc or other metal used in plating. The 65

upper portion of this loop projects above the upper end of the plate and forms a suspension means for attachment to the anode hooks R². These hooks are preferably formed with a bifurcated portion R³ for embracing pairs of bus bars Q with a central depending hook portion R⁴ which engages the loop R' and an upwardly extending hook R⁵ which may be engaged with the hoist (not shown) for lifting out from or lower- 75

With the construction as described rims or other articles to be plated, having previously been thoroughly cleansed, are fed off of inclines S into the space between links I and rollers K while said link and rollers are passing around the sprocket wheel O. At the same time the rims are resting upon the runways E which, at the end of the tank, are curved downward concentric with the 85 axis of the sprocket, so that the rims will be successively fed into the electrolyte and rolled along said runways by the propelling pressure of the contact rolls K. As the runways E are inclined upward from the entrance end to the exit end of the tank, the rims will remain always in contact with the rear roll K so as to receive the electrical current therefrom. This current is supplied through the medium of the bus bars H, 90 springs M and shafts J and as the rolls K are integral with the shafts and are in constant rolling contact with the rims, there will be a continuous supply of current to the latter. The speed of movement through the 95 electrolyte and the length of the tank is such that by the time the rims are lifted out of the solution at the discharge end, they will have been completely covered with an electrolytic deposit of sufficient thickness to 100 afford the desired protection.

What I claim as my invention is:

1. The combination with an electrolytic tank, of a cathode bus bar extending along said tank beneath the surface of the electrolyte, a work conveyor adjacent to said bus bar, a contact member for conveying the current from said bus bar into the work, and means for protecting the bus bar from direct electrolytic deposits.

2. The combination with an electrolytic tank, of a cathode bus bar extending longitudinally thereof beneath the surface of the electrolyte, an insulator trough in which said bus bar is placed, a work conveyor forming a sealing means for said trough to protect said bus bar from direct electrolytic deposits, and a conducting member carried by said work conveyor travelling in contact with said bus bar and the work propelled by the conveyor.

3. The combination with an electrolytic tank, of a cathode bus bar extending therein beneath the surface of the electrolyte, an insulator trough in which said bus bar is lo-

cated, a work conveyor having insulator members for closing said trough to protect said bus bar from direct electrolytic deposit, a conductor member carried by said conveyor 5 in travelling contact with said bus bar to receive current therefrom, and an exposed contact on said conductor bearing against the work to conduct the current thereinto.

4. The combination with an electrolytic 10 tank, of a conveyor for the articles to be plated having a portion travelling through the tank and formed of insulating material, contact members on said conveyor bearing against the work thereon, and submerged 15 means protected from direct electrolytic deposit for conveying current from the cathode to said contact.

5. The combination with an electrolytic 20 tank, of a link chain conveyor for propelling the work through said tank and formed of insulating material, contact members carried by said conveyor and bearing against the work, a cathode bus bar extending within said tank beneath the surface of the electrolyte, 25 an insulator trough surrounding said bus bar and receiving said link chain, said trough and chain protecting said bus bar from direct electrolytic deposits, and an electrical connection between said contact 30 and bus bar for conveying current into the work.

6. The combination with an electrolytic 35 tank, of a cathode bus bar therein arranged beneath the surface of the electrolyte, a trough of insulator material within which said bus bar is located, a link chain conveyor formed of insulating material and running through said trough to protect said bus bar from direct electrolytic deposits, and an 40 electrical contact member carried by said chain and maintained in electrical connection with said bus bar and with the work.

7. The combination with an electrolytic 45 tank, of an insulator frame within said tank, insulator troughs mounted on said frame oppositely facing and extending longitudinally of the tank, a work conveyor having an insulator link chain, the links thereof travelling through said troughs, cathode bus 50 bars within said troughs protected thereby and by said travelling links from direct electrolytic deposits, shafts of a conducting material extending between said links and maintained in electrical connection with 55 said bus bars, roller contacts centrally arranged on said shafts, and a runway for the work propelled by said roller contacts.

8. The combination with an electrolytic 60 tank, of a frame within said tank, pairs of troughs or channel members formed of insulator material mounted on said frame and extending parallel to and facing each other longitudinally of the tank, cathode bus bars within said troughs or channel members, a 65 conveyor chain comprising spaced links of

insulator material travelling through the channels of said troughs and forming closures therefor to protect said bus bars from direct electrolytic deposits, a shaft forming pivotal connection between longitudinally 70 adjacent links and extending between parallel spaced links, said shafts being maintained in electrical connection with said bus bars, a roller bearing at the center of said shaft for contacting with the work propelled by said conveyor and for conducting current thereinto, and insulator sleeves on said shaft between said central contact and links to protect the same from deposits.

9. The combination with an electrolytic 80 tank, of a work conveyor travelling through said tank, an electrical contact member on said work conveyor, means protected from direct electrolytic deposits for conveying current to said travelling contact, and means 85 operating on said contact when out of the electrolyte for stripping therefrom the electrolytic deposit thereon.

10. The combination with an electrolytic 90 tank, of an endless work conveyor having a portion travelling beneath the electrolyte in said tank and a return portion removed from the electrolyte, a contact member carried by said conveyor and bearing against the work, means protected from direct electrolytic deposits for conveying current into 95 said contact when passing through said electrolyte, and means operating on said contact while passing through that portion of the orbit out of the electrolyte for stripping 100 electrolytic deposits therefrom.

11. The combination with an electrolytic 105 tank, of an endless work conveyor having a portion of its orbit beneath the surface of the electrolyte in said tank and a return portion above the surface of the electrolyte, a cathode bus bar within the tank shielded from direct electrolytic deposits by said work conveyor, a contact carried by said conveyor and travelling in electrical connection with said cathode bus bar when beneath the electrolyte, and a guideway along which the work is propelled by said contact to simultaneously conduct electric current thereto.

12. The combination with an electrolytic 110 tank, of an upwardly inclined runway in said tank, a work conveyor travelling through the tank, an electrical contact on said work conveyor forming the propulsion 120 means for the work along said upwardly inclined runway, whereby electrical connection is constantly maintained therebetween.

13. The combination with an electrolytic 125 tank, of an upwardly inclined runway passing therethrough, a work conveyor, a roller contact carried by said conveyor bearing against the work and constituting a propulsion means therefor along said upwardly inclined runway, means for supplying electri- 130

cal current to said contact and means for stripping said contact of its electrolytic deposits.

14. The combination with an electrolytic tank, of a series of parallel runways in the lower portion of said tank extending longitudinally thereof and inclined upward, a series of parallel work conveyors respectively in the plane of said runways, contacts 10 on said conveyors constituting also propulsion means for the work along said runways, and bus bars shielded from electrolytic deposits by said conveyors and in electrical connection with said contacts for supplying 15 current to the work.

15. The combination with an electrolytic tank, of a runway extending longitudinally

thereof, a pair of guide-ways on opposite sides of said runway and above the same, being of channel-shaped cross section and 20 formed of insulating material, cathode bus bars in said guide-ways, a work conveyor including a link chain of insulator material, links travelling in said guide-ways and shielding the bus bars therein from electrolytic deposits, shafts forming a pivotal connection for said links and extending 25 across the space between said guide-ways, contact rollers at the center of said shafts, and sleeves of insulating material for protecting said shafts from electrolytic deposits. 30

In testimony whereof I affix my signature.

LEWIS V. MATHER.
